[57] CLAIM

The ornamental design for a fast fare processor unit,
substantially as shown.

DESCRIPTION

FIG. 1 is a top, front, and right side perspective view of
a fast fare processor unit showing my new design;

FIG. 2 is a bottom plan view thereof;

FIG. 3 is a front end elevational view thereof;

FIG. 4 is a rear end elevational view thereof; and

FIG. 5 is a left side elevational view thereof.
